UNITED STATES PATENT OFFICE

2,446,092

BOAT RACK MEANS ON AUTOMOBILES

Morris Lait, Lynn, Mass.

Application April 14, 1947, Serial No. 741,245

3 Claims. (Cl. 214—77)

1

My invention relates to improvements in boat racks for use in carrying small boats on top of automobiles.

A primary object of my invention is to provide a simple form of boat rack adapted for easy attachment to or detachment from tops of the usual closed automobiles, without injury thereto or marring the same, and which is especially constructed and arranged so that one man may load the usual row boat or the like, onto such tops or unload the same with comparative ease and without danger of injuring himself, or the boat.

Another object is to provide a device of the character and for the purpose above indicated which provides for turning the boat and inclining the same in a manner facilitating lifting and lowering the boat in loading and unloading operations.

Other and subordinate objects, also comprehended by my invention, together with the precise nature of my improvements and the advantages thereof will be readily understood when the succeeding description and claims are read with reference to the drawings accompanying and forming part of this specification.

In said drawings:

Figure 1 is a fragmentary view in side elevation of my improved boat rack in a preferred embodiment thereof attached to the top of an automobile with the boat loaded thereon as shown in broken lines;

Figure 2 is a fragmentary view in rear elevation;

Figure 3 is a view in side elevation illustrating one of the fasteners for attachment to the oar lock of the boat;

Figure 4 is a view in edge elevation of the same;

Figure 5 is a view in perspective of the type of oar lock bracket in which the fastener is designed for use;

Figure 6 is a view in perspective illustrating the use of the boat rack in lowering a boat to the ground and raising the same in loading and unloading operations;

Figure 7 is a view in rear elevation illustrating operation of the rack in swinging the boat into loaded position;

Figure 8 is a view in perspective illustrating the boat in loaded position.

Referring now to the drawings by numerals, my improved boat rack, designated generally by the numeral 1, comprises, in the embodiment shown, a pair of front and rear base bars 2, 3 of any suitable light strong material and which are adapted to extend across the top 4 of a closed automobile body 5 adjacent to the front and rear of said top.

2

End brackets 6 of bar metal, preferably, and substantially inverted U-shape, are bolted, as at 8, to the ends of said bars 2, 3 to extend crosswise of the same and support said bars slightly elevated above said top 4. Rubber, or other resilient material feet 8 are provided on said brackets 6 to prevent the same from marring the top 4 and slipping thereon.

Attaching straps 9, with buckles 10 for length adjustment of the same are passed through metal end loops 11 on the underside of said bars 2, 3 and provided with grapple hoops 13 which are adapted to engage under the usual side channel beads 14 on the automobile body 5 whereby said bars 2, 3 may be easily attached on said top 4, or, detached therefrom.

A boat turning bar 15 with right angled ends 16 has one end pivoted by a horizontal bolt 17 to an upstanding arm 18 of an angle bracket the horizontal arm 18 of which is pivoted by a vertical bolt 20 to the end of the front bar 2 disposed at the right hand side of the automobile body 5. The other end 16 of said bar 15 is pivoted by a horizontal spindle bolt 21 of a grooved wheel 22.

An arcuate track bar 23, on which the grooved wheel 22 is fitted, is bolted at one end as at 23', on the end of the rear bar 3 at the right hand side of the automobile body 5 to extend horizontally to the end of the front bar 2 at the left hand side of said automobile body 5. The track bar 23 is curved in an arc having the vertical bolt 20 as its center and connects the front and rear bars 2, 3 rigidly in spaced apart parallel relation.

As will now be seen, the boat turning bar 15 is swingable vertically about the axis of the bolts 17, 21, which is to say about a horizontal axis, into and from an upright position and is also swingable about the axis of the vertical bolt 20, which is to say a vertical axis, laterally over the track bar 23 to position the same crosswise of the top 4, over the front bar 2, or, into a longitudinally extending position alongside the right hand side of the top 4.

Boat fasteners are provided on the boat turning bar 15 for securing on top thereof, in inverted position, a boat 24 of the type having a pair of opposite front oar lock brackets 25 each with a vertical oar lock aperture 26 therein.

The boat fasteners comprise a pair of crank disks 27 rotatably mounted on bearing brackets 28 straddling the boat turning bar 15 and suitably fixed thereto adjacent opposite ends thereof with the crank disks 27 coplanar with said bar and rotatable about axes transverse to said bar,

A pair of upstanding pins 29 adjacent said brackets 28, intermediate the same, are suitably fixed to said bar 15 to extend part way through the oar lock apertures 26 when the boat 24 is inverted over said bar 15. A pair of L-shaped latch hooks 30 are pivoted at one end, as at 31, on the crank disks 27 eccentrically for positioning of the other ends thereof over said apertures 26, and lowering of said other ends part way into said apertures 26 by rotation of said crank disks 27. Suitable handles 32 provide for rotating said crank disks 27 to revolve the pivots 31 into dead center position relative to the axis of the crank disks 27 to latch the catch hooks 30 against the pins 29 and thereby lock the described fasteners closed.

In using the described boat rack in loading the boat 24 thereon, the boat turning bar 15 is swung into longitudinally extending position on the top 4 alongside the right hand side of said top, as shown in Figure 6. With the boat 24 tilted on the stern thereof, on the ground, or the like, to incline upwardly over the top 4 on the right hand side of the automobile body 5, said bar 15 is swung on its horizontal axis to incline the pins 29 toward said boat, as shown in Figure 6, and the boat 24 is then maneuvered so as to insert the pins 29 part way into the oar lock apertures 26, it being of course understood that in this operation the open side of the boat is positioned to face the automobile body 5. With the catch hooks 30 suitably held by hand, the handles 32 are swung to insert said hooks into said apertures 26 and to lock the fasteners in the manner already described. The boat 24 may then be lifted by its stern, as shown in Figure 7, sufficiently to clear the rear bar 3, the boat turning bar 15 turning in this operation about its horizontal axis into upright position. Then the boat 24 may be swung into a position of rest to extend longitudinally of the top 4 with its rear portion resting on the rear bar 3, the boat turning bar 15 swinging in this operation about its vertical axis and being supported at its free end by the grooved wheel 22 running on the track bar 23. In unloading the boat 24, the procedure is substantially the reverse of that described for loading, and, will be understood without further explanation.

The foregoing will, it is believed, suffice to impart a clear understanding of my invention, without further explanation.

Manifestly, the invention, as described, is susceptible of modification without departing from the inventive concept, and right is herein reserved to such modifications as fall within the scope of the appended claims.

I claim:

1. A rack for use in loading and carrying on top of an automobile body, of the type having upper side beads, an inverted row boat having oar lock brackets, said rack comprising a pair of front and rear base bars adapted to extend across the front and rear of said top, a boat turning bar pivotally connected at one end to one end of the front base bar to be swung horizontally parallel with said front bar from a position in which the same extends longitudinally of said body, means supporting the other end of said boat turning bar during swinging thereof, fasteners on said boat turning bar adapted for attachment to said brackets whereby said boat may be attached on top of the boat turning bar to be swung into a

position of rest on the rear base bar and thereby swing said turning bar parallel with the front base bar to support said boat while being swung, and means to attach said bars on said top and to said beads, said supporting means comprising an arcuate track rigidly connecting said base bars and a roller on said turning bar running on said track.

2. A rack for use in loading and carrying on top of an automobile body, of the type having upper side beads, an inverted row boat having oar lock brackets, said rack comprising a pair of front and rear base bars adapted to extend across the front and rear of said top, a boat turning bar pivotally connected at one end to one end of the front base bar to be swung horizontally parallel with said front bar from a position in which the same extends longitudinally of said body, means supporting the other end of said boat turning bar during swinging thereof, fasteners on said boat turning bar adapted for attachment to said brackets whereby said boat may be attached on top of the boat turning bar to be swung into a position of rest on the rear base bar and thereby swing said turning bar parallel with the front base bar to support said boat while being swung, and means to attach said bars on said top and to said beads, said pivotal connection providing for turning of the boat turning bar about an horizontal axis to facilitate attaching of said fasteners to said brackets.

3. A rack for use in loading and carrying on top of an automobile body, of the type having upper side beads, an inverted row boat having oar lock brackets, said rack comprising a pair of front and rear base bars adapted to extend across the front and rear of said top, a boat turning bar pivotally connected at one end to one end of the front base bar to be swung horizontally parallel with said front bar from a position in which the same extends longitudinally of said body, means supporting the other end of said boat turning bar during swinging thereof, fasteners on said boat turning bar adapted for attachment to said brackets whereby said boat may be attached on top of the boat turning bar to be swung into a position of rest on the rear base bar and thereby swing said turning bar parallel with the front base bar to support said boat while being swung, and means to attach said bars on said top and to said beads, said pivotal connection providing for turning of the boat turning bar about an horizontal axis to facilitate attaching of said fasteners to said brackets.
